(57) **CLAIM**

The ornamental design for an electrical connector as shown and described.

DESCRIPTION

FIG. 1 is a top front right perspective view of an electrical connector showing our new design;

FIG. 2 is a top rear left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The figures include broken, solid and dash-dot-dash lines. The areas within the solid lines form the claimed design. The dash-dot-dash lines illustrate an unclaimed boundary of the claimed design. The broken lines shown in the figures are included for the purpose of illustrating portions of the electrical connector and form no part of the claimed design.
